(57) **CLAIM**

I claim the ornamental design for the light fixture, as shown and described.

DESCRIPTION

FIG. 1 is a side elevation view of a broad side of a six-sided light fixture showing my new design, all six sides being the same;

FIG. 2 is a side elevation view of a point-side of a six-sided light fixture, all six points being the same.

FIG. 3 is top plan view of the light fixture; and,

FIG. 4 is a bottom plan view of the light fixture.
